UNITED STATES PATENT OFFICE.

REINHOLD A. NORLING, OF AURORA, ILLINOIS, ASSIGNOR TO AURORA AUTOMATIC MACHINERY COMPANY, OF AURORA, ILLINOIS, A CORPORATION OF ILLINOIS.

PNEUMATIC HAMMER.

1,027,062.

Specification of Letters Patent. Patented May 21, 1912.

Application filed December 17, 1910. Serial No. 597,864.

To all whom it may concern:

Be it known that I, REINHOLD A. NORLING, a citizen of the United States, and a resident of Aurora, in the county of Kane and State 5 of Illinois, have invented certain new and useful Improvements in Pneumatic Hammers; and I do hereby declare that the following is a full, clear, and exact description thereof, reference being had to the accompanying drawings, and to the letters of reference marked thereon, which form a part 10 of this specification.

This invention relates to a portable pneumatic tool or hammer of that class embracing a barrel or cylinder, a piston or plunger adapted to move therein, and a controlling valve, through which the air or other fluid under pressure is admitted to and permitted to escape from the opposite 20 ends of the cylinder or barrel to give reciprocatory movement to the plunger therein.

The invention is illustrated and described herein as applied to a chipping hammer, otherwise known as a short stroke hammer 25 and consists of the combination of parts hereinafter described and more particularly pointed out in the appended claims.

In the drawings:—Figure 1 is a longitudinal section through the hammer in a plane 30 containing the central axis of the barrel or cylinder and the central axis of the throttle valve chamber. Fig. 2 is a longitudinal section on an enlarged scale through the barrel in a plane through the central axis there- 35 of at an angle to the plane of Fig. 1. Fig. 3 is a similar section through the barrel in the same plane showing the piston and movable valve member in different positions from those shown in Fig. 2. Fig. 4 is a 40 longitudinal section through the central axis of the barrel in a plane at a second angle to the plane of the section of Fig. 1. Figs. 5, 6, 7, and 8 are longitudinal sections through the barrel taken respectively on the lines 45 5—5, 6—6, 7—7 and 8—8 of Fig. 9. Fig. 9 is a rear end elevation of the barrel. Fig. 50 10 is a cross section through the head of the hammer on the line 10—10 of Fig. 3. Fig. 11 is a cross-section on the line 11—11 of Fig. 3. Fig. 12 is a cross-section on the line 12—12 of Fig. 2. Fig. 13 is a side elevation 55 of the valve block body. Fig. 14 is a transverse section through the valve block body on the line 14—14 of Fig. 13. Fig. 15 is a longitudinal section through the valve block

body on the line 15—15 of Fig. 14. Fig. 16 is a side elevation of the valve block cap. Fig. 17 is a transverse section through said valve block cap on the line 17—17 of Fig. 16. Fig. 18 is a longitudinal section through the valve block cap on the line 18—18 of Fig. 17. 60

In that embodiment of my invention illustrated in the accompanying drawings, A represents the barrel or cylinder of the hammer; B, the piston or plunger adapted to reciprocate therein; C, the tool carrying nozzle; and D, the tool, in this case a chisel. The rear end of the barrel or cylinder is screw-threaded as at a, to receive the forward, internally threaded end of a hollow head E. Said hollow head E is closed at its rear end by an end wall E¹ and has formed integrally with it a handle F. The head E is split at its forward end and provided with a longitudinal recess e inclosed by apertured lugs e¹, e¹ which are drawn together by a bolt e² so as to rigidly clamp the thread of the head in engagement with the thread of the barrel. 70

G indicates a transverse passage in the tool head containing a valve bushing g.

G¹ is a throttle valve piston reciprocably mounted in said bushing, and adapted to be operated by a stem G² which projects through an aperture G³ into a slot G⁴ in the handle containing a pivotally mounted lever G⁵ which operatively engages the upper end of said stem. Said lever G⁵ is actuated by a hand lever or trigger F¹ pivotally mounted in the slot G⁴ in position to be engaged by the palm of the hand when the tool handle is grasped and connected to said lever G⁵ by a link f. An annular chamber g¹ is formed about the bushing g and is connected with the interior thereof by supply ports g². 85 90 95

g³ is an air passage leading to the annular chamber g¹. Said passage is enlarged at its outer end and threaded to receive the usual air supply pipe (not shown). The outer end of the transverse passage G is closed by a threaded cap g⁴ and the opposing parts of said cap and of the piston valve G¹ are provided with recesses to receive the ends of a coiled spring g⁵ which normally holds the piston in position to close the supply ports g². 100 105

The valve mechanism for controlling the admission and exhaust of air into and from the cylinder embraces a valve block H¹ provided with exhaust and admission ports and 110

an annular or cylindric valve ring *J* surrounding said valve block and arranged to slide endwise thereon to open and close said ports; said valve ring being provided with 5 oppositely facing differential pressure areas. Said valve block is located at the rear end of the barrel and is made in two parts,—a body member *H* and a cap member *I*.

The valve block body *H* rests at its forward end within an annular recess *a*¹ formed in the rear end of the piston barrel *A*. It is provided with a longitudinal bore of a diameter slightly greater than that of the piston barrel *A* and co-axial therewith. 10 A dowel pin *h* (see Figs. 2 and 3) holds said valve block body against rotative movement relative to the piston barrel. The cap member *I* is provided at its forward end with a short annular projection *I*¹ which engages 15 within the bore of the valve block body. Its rear end rests against the end wall *E*¹ of the plunger barrel head. The valve block *H*^x is thus rigidly held in place between the rear end of the cylinder *A* and the end wall 20 of the hollow head *E*. A dowel pin *i* (see Figs. 2 and 3) holds the cap *I* against rotative movement relative to the valve block body *H*.

The valve member *J* is in the form of a 25 cylindric sleeve surrounding the valve block *H*^x and is arranged to have endwise sliding movement thereon. The valve block *H*^x is enlarged in diameter at its forward end to form an annular flange *H*¹. The valve ring 30 *J* is enlarged at its forward end to embrace said flange *H*¹ and is provided with an annular shoulder *J*¹ on its inner surface which is opposed to the rear face of the annular flange *H*¹, and which forms the larger 35 pressure area of the valve ring. The valve block cap *I* is made of larger diameter than the rear end of the valve block body *H* so as to form a forwardly facing, annular shoulder *I*² extending around the rear end of the 40 body, and the valve ring *J* is enlarged at its rear end, as indicated at *J*⁴, to embrace said valve block cap. *J*⁵ indicates an annular rearwardly facing shoulder on the inner surface of the valve ring *J* opposite the forwardly facing annular shoulder *I*² of the 45 valve block. Said shoulder *J*⁵ constitutes the smaller pressure area of the valve ring *J*. Within the inner, rear, enlarged end of the valve ring is formed an annular groove 50 or channel *J*⁶ which is adapted to be brought into communication with the space between the shoulder *J*⁵ of the valve ring and the shoulder *I*² of the valve block when the valve ring has moved to the forward limit of its 55 movement, as shown in Figs. 3 and 4. The forward movement of the valve ring *J* is limited by the rear end of the cylinder *A*, while its rearward movement is limited by the end wall *E*¹ of the hollow head *E*. The 60 length of the valve ring *J* is so proportioned 65

to the distance between the end wall *E*¹ and the rear end of the cylinder *A* that the shoulders *J*¹ and *J*⁵ of the valve ring do not strike the shoulders of the valve block to which they are opposed when the valve ring moves to its limits, but leave a small space between them (see Figs. 2 and 3) so that air may be readily admitted to the pressure areas of the valve ring.

K indicates a set of longitudinal exhaust passages formed in the wall of the barrel *A* near its rear end and extending into the wall of the valve block to an annularly arranged series of exhaust ports *K*² which open through the outer surface of valve block near its forward end. Said exhaust ports are in the form of transverse slots in the outer surface of the valve block body *H*, there being a slot for each pair of longitudinal ports *K* of which there are four pair as shown in the drawings (see Figs. 4, 7, 10 and 13). Said passages *K* communicate with the interior of the barrel by means of ports *K*¹ near its rear end, which ports are adapted to be closed by the piston when it nears the inner end of its return stroke. Said passages *K* and ports *K*¹ and *K*² constitute the main exhaust passages or ports for the inner end of the cylinder and are adapted to permit the exhaust of the air from the inner end of the barrel, when the piston *B* is making its rearward or return stroke, the valve ring *J* being then in such position that the ports *K*² are uncovered and open to the space *X* about the valve, which space is freely open to the outer air through the passage *X*¹ (see Fig. 1) which opens through the cylindric wall of the head *E*.

M indicates passages extending longitudinally through the walls of the main barrel or cylinder and which open into the interior of the barrel at its forward end through ports *m* (see Figs. 1, 5 and 10), and which are adapted for the exhaust of air from the outer or forward end of the cylinder during the outward stroke of the piston. Said passages extend into the walls of the valve block *H* and each opens into a plurality, in this case four, longitudinal passages *M*¹ of smaller diameter which extend into the valve block cap *I* to points adjacent the rear end of said cap where said passages open through the outer surface of the cap by means of ports *M*². Said ports are in the form of transverse slots in the outer surface of the cap (see Figs. 12 and 16) and are covered by the valve ring *J* when the same is at the rearward limit of its movement but are left uncovered and open to the exhaust space *X* when said valve ring is at its forward limit of movement. From the foregoing description it will be apparent that when the valve ring *J* is at the rearward limit of its movement, the exhaust space *X* is connected with the inner or rear end of 105 110 115 120 125 130

the barrel, while, when said valve ring is at the forward limit of its movement, said exhaust space is connected with the outer or forward end of the barrel.

- 5 In the rear end of the valve block cap I is formed a central annular recess or chamber I^3 which opens directly into the transverse throttle-valve passage G in the head. A series of annularly arranged radial ports I^4 are provided in the cylindric wall of the cap I, said ports extending from the chamber I^3 through the outer surface of said cap and being inclined slightly to a plane at right angles to the longitudinal central axis 10 of the cap so as to open into the annular space formed by the channel J^6 of the valve ring in all positions thereof. (See Figs. 2, 3 and 4). The space formed by the channel J^6 is thus always supplied with live air when 20 the throttle valve is open.

In the rear end of the valve block body H are provided a series of annularly arranged radial ports R, which extend through the walls of said valve block body and constitute the main supply ports for admitting air to the inner end of the cylinder. Said ports are adapted to be uncovered and brought into communication with the annular groove or channel J^6 of the valve ring 25 J for the admission of air to the inner end of the cylinder when the valve ring J is in its forward position. (See Fig. 4).

N indicates a longitudinal passage (see Figs. 1, 5, 8, 15 and 18) formed in the wall of the cylinder A and extending through the valve block body H and into the cap I where it connects at its rear end with one of the radial ports I^4 leading from the live air chamber I^3 in said cap. N^1 is a parallel longitudinal passage formed in the wall of the chamber A and spaced circumferentially from the passage N. Said passage N^1 extends through the valve block body H and opens at its rear end through a port N^2 40 opening through the outer surface of the valve block body into the space between the annular shoulder J^6 , that is to say, the smaller pressure area of the valve ring, and the annular shoulder I^2 of the valve block. At their forward ends the passages N and N^1 are connected by a transverse slot n formed in the inner surface of the barrel. The smaller pressure area of the valve ring 45 when the piston B is in a position to cover the slot n is thus subjected to the live air pressure by reason of the live air passing through the port N^2 , the passage N^1 , the slot n , the passage N and the connected radial port I^4 which opens into the live air chamber I^3 in the valve block cap.

Some of the longitudinal exhaust passages M^1 which lead to the forward end of the barrel, as shown in the drawings two of each four located on opposite sides of the valve block, open by ports P (see Figs. 1,

16 and 17) into slots P^1 formed in the outer cylindric surface of the valve block cap I and spaced longitudinally to the rear of the exhaust ports M^2 . The slots P^1 open into the live air space formed by the groove or channel J^6 when the valve ring J is in its rearward position and are closed by said valve ring when the same is in its outer or forward position. The slots P^1 , ports P and the longitudinal passages M^1 connected therewith, constitute the supply ports for admitting air to the outer or forward end of the cylinder to drive the piston rearward on its return stroke.

Q indicates a longitudinal supply passage 80 formed in the wall of the cylinder A and extending into the valve block body and opening by a port Q^1 into the space between the annular shoulder formed by the flange H^1 of the valve block and the annular shoulder J^1 , that is to say, the larger pressure area of the valve ring. The passage Q opens by a port Q^2 into the cylinder at a point intermediate its ends. Said port Q^2 is adapted to be uncovered by the rear end 90 of the piston B on its power or forward stroke just prior to its completion of said stroke, so as to permit the live air in the rear end of the cylinder to act on the larger pressure area of the valve ring and shift 95 said ring against the live air pressure on its smaller pressure area, to its rearward position. The passage Q is extended forwardly beyond the port Q^2 to a point intermediate 100 said port and the forward end of the cylinder where it opens into said cylinder through a second port Q^3 which is closed by the piston when the port Q^2 is uncovered to admit live air to shift the valve ring rearwardly, and which is uncovered by the forward end 105 of the piston on its return stroke. An auxiliary longitudinal exhaust passage T is formed in the wall of the cylinder, said passage opening at its rear end by a port T^1 (see Figs. 2 and 8) through the wall of the 110 rear end of said cylinder into the exhaust space X and opening at its forward end by a port T^2 into the cylinder at a point longitudinally spaced to the rear of the port Q^3 and adapted to be uncovered by the forward end of the piston on its return stroke after it has uncovered the port Q^3 . By this construction the passage Q leading to the 115 larger pressure area J^1 of the valve ring is connected to the exhaust space X after the forward end of the piston has passed the port T^2 on the return stroke, through the port Q^3 , the cylinder, the port T^2 , the passage T and the port T^1 . This relieves the 120 live air pressure on the larger pressure area of the valve ring, so that it may be shifted to its forward position by live air pressure on its smaller pressure area when the rear end of the piston reaches and incloses the slot n , and the live air, passing through 125 130

the passage N from the connected radial port I⁴ in the valve block cap, instead of escaping with the rest of the exhaust from the rear end of the cylinder through exhaust ports and passages K¹, K, K², is directed by means of said slot n through the passage N¹ and the port N² to said smaller pressure area.

- The operation of the valve mechanism is as follows: Starting with the parts in the position indicated in Fig. 4, with the plunger at the inner or rear end of its stroke, and the valve ring J at the outer or forward limit of its movement, the main supply ports R for admitting live air to the rear end of the cylinder are open into the channel or groove J⁶ of the valve ring and the exhaust ports M² through which the exhaust from the forward end of the cylinder passes to the exhaust space X are also open. The opening of the throttle valve G¹ admits live air to the live air chamber I³ in the valve block cap I whence it passes through the radial ports I⁴ in said cap to the channel or groove J⁶ and thence through the ports R to the inner end of the cylinder. A large supply of air is thus admitted to drive the piston with force forwardly on its working or power stroke, and the air at the forward end of the cylinder in advance of the piston is exhausted through the ports m, the passages M, M¹ and the exhaust ports M². As the piston nears the end of its forward stroke and reaches the position indicated in Fig. 3, its forward end covers the port Q³ and its rear end uncovers the port Q² thus permitting the live air at the inner end of the cylinder to pass through the passage Q and port Q¹ to the larger pressure area J¹ of the valve ring. This effects a movement of the valve ring J to the rearward limit of its movement against the live air pressure on its smaller pressure area J⁵ which it receives through the port N², the passage N¹, the slot n, the passage N and the associated port I⁴ in the valve block cap. This rearward movement of the valve ring uncovers the exhaust ports K² for the rear end of the cylinder, opens the supply ports P¹, adapted to admit live air to the forward end of the cylinder, into communication with the channel or groove J⁶ of the valve ring which contains live air, and closes the exhaust ports M² and the main supply ports R adapted, respectively, for the exhaust from the forward end of the cylinder and for the supply of live air to the rear end of the cylinder. In the meantime the piston has reached the outer or forward limit of its movement and under the pressure of live air passing through the ports P¹, and the associated passages and ports P M¹, M and m, is driven on its return or rearward stroke. At the beginning of the return stroke and prior to the time the piston reaches the po-

sition indicated by dotted lines in Figs. 1 and 2, the live air entering the rear end of the cylinder through the passage N and the associated radial port I⁴ in the valve block cap, escapes with the rest of the exhaust from the rear end of the cylinder through the exhaust ports K², so that it has no effect on the smaller pressure area J⁵ of the valve ring. Just before the piston reaches the last referred to position, its forward end uncovers the ports Q³ and T², thereby opening the larger pressure area J¹ to the exhaust space X, through the port Q¹, the passage Q, the port Q³, the cylinder, the port T² and the auxiliary exhaust passage and ports T, T¹, so that, when it reaches the said position and its forward end incloses the slot n so as to direct the live air entering through the passage N into the passage N¹ and thence through the port N² to the smaller pressure area J⁵ of the valve ring, a forward movement of said valve ring is effected since there is now no pressure on the large pressure area of the valve ring. This puts the parts in the first position described with the exhaust ports K² for the inner or rear end of the cylinder and the supply ports P¹ for the forward end of the cylinder closed, and the supply ports R for the inner or rear end of the cylinder and the exhaust ports M² for the outer or forward end of the cylinder open. The operation then continues as before.

The ports K¹ which connect the interior of the cylinder with the exhaust passages for the exhaust from the inner or rear end of the cylinder are located, as shown in the drawings, forward of the rear end of the cylinder A and in such position that they will be closed on the return stroke by the rear end of the piston B almost immediately after said rear end of the piston has inclosed the slot n so as to direct the live air to the smaller pressure area of the valve ring J to effect its forward movement. The piston thus immediately cuts off the exhaust from the inner or rear end of the cylinder, independently of the action of the valve ring J, so that the air still remaining in the rear end of the cylinder will be compressed by the piston as it finishes its return stroke and will act as an air cushion. While this arrangement is not essential, since the valve ring J is shifted by live air in both directions, still it is preferable, in order to prevent any possibility of the piston striking the valve block cap, in case the action of the valve should be slow for any reason, as when it becomes "gummed" or when the throttle valve is but slightly opened so that only a small amount of air is admitted to shift the valve ring.

In Figs. 1, 13 and 14 there is shown a small leak port n¹ connecting the live air passage N which supplies air to the smaller

pressure area of the valve, with the space between the annular shoulder formed by the flange H^1 of the valve block body and the annular shoulder J^1 or larger pressure area of the valve. This is provided in order to start the tool when the piston is at the outer or forward limit of its movement and the valve ring is in its forward position, as may happen when the tool is idle and is held in a vertical position with its forward end down, and the valve ring falls by gravity into the position referred to.

It will be seen from this description that the controlling valve of my improved hammer is a valve of differential area in which the pressure on both areas of the valve is intermittent, neither pressure being a constant one, for though the smaller pressure area is always open to live air pressure, the live air, by reason of the slot n has no effect on the smaller pressure area during the return stroke of the piston since it escapes during the return stroke of the piston from the passage N through the slot n into the cylinder and thence with the rest of the exhaust through the exhaust ports for the inner end of the cylinder. At one instant only, namely, at the time when the valve is shifted from its outer to its inner position, pressure is exerted on both ends of the valve.

I claim as my invention:—

1. The combination with a cylinder and a reciprocating plunger therein, of a controlling valve for controlling the admission and exhaust of air into and from the cylinder embracing an annular valve having oppositely facing differential pressure areas, means controlled by the plunger for admitting live air to the larger pressure area of the valve, and means affording a continuous passageway for live air to the smaller pressure area of the valve, said means including a port opening into the cylinder and adapted to be closed by said plunger when the rear end of the cylinder is open to the exhaust.

2. The combination with a cylinder and a reciprocating plunger therein, of a controlling valve for controlling the admission and exhaust of air into and from the cylinder embracing a valve block provided with a live air chamber in its rear end, a valve ring having oppositely facing differential pressure areas, means controlled by the plunger for admitting live air to the larger pressure area of the valve, and means affording a continuous passageway from said live air chamber to the smaller pressure area of the valve, said means including a port opening into the cylinder near its rear end and adapted to be closed by the piston when it approaches the end of its return stroke.

3. The combination with a cylinder and a reciprocating plunger, of a controlling valve for controlling the admission and exhaust

of air into and from the cylinder embracing a valve block provided with a live air chamber at its rear end and a hollow valve having oppositely facing differential pressure areas adapted to move endwise on said valve block, said valve block having two longitudinally spaced sets of exhaust and supply ports near its opposite ends, the sets of admission ports being adjacent, a channel formed in said hollow valve adapted, in the endwise movement thereof, to communicate with each set of admission ports in alternation, means providing a constant supply of live air to said channel, means controlled by the piston for admitting live air to the larger pressure area of the valve, and means affording a continuous passageway from said live air chamber in the valve block to the smaller pressure area of said valve, said means including a port opening into the cylinder and adapted to be closed by the piston on its return stroke.

4. The combination with a cylinder and a reciprocating plunger, of a controlling valve for controlling the admission and exhaust of air into and from the cylinder embracing a valve block provided with a live air chamber at its rear end and a hollow valve having oppositely facing differential pressure areas adapted to move endwise on said valve block, said valve block having two longitudinally spaced sets of exhaust and admission ports near its opposite ends, the sets of admission ports being adjacent, a channel formed in said hollow valve adapted, in the endwise movement thereof, to communicate with each set of admission ports in alternation, supply ports in said valve block connecting said live air chamber with the channel in said hollow valve in all positions thereof, means controlled by the piston for admitting live air to the larger pressure area of the valve, and means affording a continuous passageway from said live air chamber in the valve block to the smaller pressure area of said valve, said means including a port opening into the cylinder and adapted to be closed by the piston on its return stroke.

5. The combination with a cylinder and a reciprocating plunger therein, of a controlling valve for controlling the admission and exhaust of air into and from the cylinder embracing an annular valve having oppositely facing differential pressure areas, means controlled by the plunger for admitting live air to the larger pressure area of the valve, a passageway open at its rear end to a constant supply of live air, a second passageway adapted to supply air to the smaller pressure area of said valve, and a slot opening into said cylinder and connecting the forward ends of said passageways, said slot being adapted to be closed by the piston on its return stroke.

6. The combination with a cylinder and a reciprocating plunger therein, of a controlling valve for controlling the admission and exhaust of air into and from the cylinder embracing a valve block member and a valve ring member, said valve ring member having oppositely facing differential pressure areas and being adapted to move endwise on said valve block, said valve block member having shoulders of different areas opposing the pressure areas of said valve ring, a circumferentially extending channel in said valve ring located at the rear of the smaller pressure area thereof, means providing a constant supply of live air to said channel, and admission ports in said valve block member located on opposite sides of the shoulder thereof of smaller area, said valve ring being constructed to connect said channel in its endwise movement with said ports in alternation.

7. In combination with a cylinder and a reciprocating plunger therein, of a controlling valve controlling the admission and exhaust of air into and from the cylinder, embracing an annular valve having oppositely facing differential pressure areas, means affording a continuous passageway for live air to the smaller pressure area of the valve, said means including a port opening into the cylinder and adapted to be closed by said plunger when the rear end of the cylinder is open to the exhaust, and means for controlling the pressure on the larger pressure area of the valve, embracing a passageway opening at its rear end by a port leading to said larger pressure area and opening at its forward end into the cylinder by an admission port and by an exhaust port, the exhaust port being spaced forward of the admission port, said admission port being adapted to be uncovered by the rear end of the piston on its outward stroke, and said exhaust port being adapted to be covered by the forward end of the piston on its outward stroke and to be uncovered thereby on its return stroke.

8. The combination with a cylinder and a reciprocating plunger therein, of a controlling valve for controlling the admission and exhaust of air into and from the cylinder embracing an annular valve having oppositely facing differential pressure areas, means controlling the supply of air for the smaller pressure area of said valve embracing a passageway open at its rear end to a constant supply of live air, a second passageway adapted to supply air to the smaller pressure area of said valve, and a slot opening into said cylinder and connecting the forward ends of said passageways, said slot being adapted to be closed by the piston on its return stroke, and means for controlling the pressure on the larger pressure area of the valve, embracing a pas-

sageway opening at its rear end by a port leading to said larger pressure area and opening at its forward end into the cylinder by an admission port and by an exhaust port, the exhaust port being spaced forward of the admission port, said admission port being adapted to be uncovered by the rear of the piston on its outward stroke, and said exhaust port being adapted to be covered by the forward end of the piston on its outward stroke and to be uncovered thereby on its return stroke prior to the time that said slot is covered by the rear end of the piston.

9. The combination with a cylinder and a reciprocating plunger therein, of a controlling valve for controlling the admission and exhaust of air into and from the cylinder embracing a bearing member formed at the inner end of the cylinder and a valve ring adapted to slide thereon, said valve ring having oppositely facing, differential pressure areas and being adapted to move endwise on said bearing member, said bearing member having two longitudinally spaced shoulders of different areas opposing the pressure areas of said valve ring, a circumferentially extending channel in said valve ring located at the rear of the smaller pressure area thereof, means providing a constant supply of live air to said channel, exhaust ports located at opposite ends of the valve bearing member for the exhaust respectively from the rear end and from the forward end of the cylinder, and longitudinally spaced admission ports located intermediate the ends of said bearing member adapted for the supply of air respectively to the rear and to the outer end of said cylinder, said channel in said ring member being constructed to communicate with said admission ports in alternation when said valve ring member is at the opposite limits of its movement.

10. The combination with a cylinder and a reciprocating plunger therein, of a controlling valve for controlling the admission and exhaust of air into and from the cylinder embracing a valve block located at the rear end of the cylinder and a valve ring adapted to slide thereon, said valve ring having oppositely facing, differential pressure areas and being adapted to move endwise on said valve block, and said valve block having two longitudinally spaced shoulders of different areas opposing the pressure areas of said valve ring, a circumferentially extending channel in said valve ring located at the rear of the smaller pressure area thereof, a live air chamber located in the rear end of said valve block, ports connecting said live air chamber with the channel in said valve ring in all positions thereof, exhaust ports located at opposite ends of the valve block for the exhaust respectively from the rear end and from

the forward end of the cylinder, and two longitudinally spaced sets of admission ports located intermediate the ends of said bearing member adapted for the supply of 5 air respectively to the rear and to the outer end of said cylinder, said channel in said ring members being constructed to communicate with said sets of admission ports in alternation when said valve ring member is 10 at the opposite limits of its movement.

11. The combination with a cylinder and a reciprocating plunger therein, of a controlling valve for controlling the admission and exhaust of air into and from the cylinder embracing a valve block located at the inner end of the cylinder and a valve ring 15 adapted to slide thereon, said valve ring having oppositely facing, differential pressure areas and being adapted to move end- 20 wise on said valve block, and said valve block comprising a body member bored to form a prolongation of said cylinder and a cap member inclosing the rear end of said cylinder, said valve block having two lon- 25 gitudinally spaced shoulders of different areas opposing the pressure areas of said valve ring, a circumferentially extending channel in said valve ring located at the rear of the smaller pressure area thereof, 30 a live air chamber in said valve block cap, ports in said valve block cap connecting said chamber with said channel of said valve ring in all positions thereof, exhaust and supply ports for the inner end of the cylinder lo- 35 cated respectively at the forward and rear ends of said valve block body, and exhaust and admission ports for the forward end of the cylinder located in said valve block cap, the admission ports for both ends of the 40 cylinder being longitudinally adjacent, and said channel in said ring member being constructed to communicate with said admission ports for the opposite ends of the cylinder in alternation when said valve ring member 45 is at the opposite limits of its movement.

12. The combination with a cylinder and a reciprocating plunger therein, of a controlling valve for controlling the admission and exhaust of air into and from the cylinder embracing a valve block located at the inner end of the cylinder and a valve ring 50 adapted to slide thereon, said valve block comprising a body having a bore forming a prolongation of the cylinder and a cap member closing said bore, said valve ring 55 having oppositely facing, differential pressure areas adapted to move endwise on said valve block, and said valve block having two longitudinally spaced shoulders of different areas opposing the pressure areas of said valve ring, a circumferentially extending channel in said valve ring located at the rear of the smaller pressure area thereof, means providing a constant supply of live 60 air to said channel, a set of exhaust and admission ports for the rear end of the cylinder opening through the outer surface of the valve block body respectively at its forward and rear ends, an exhaust passage leading from the forward end of the cylinder 65 and opening at a point near the rear end of the valve block cap by a port through the annular surface thereof, and an admission port connected with said exhaust passage and opening through the outer annular sur- 70 face of said cap at a point forward of said exhaust port, said channel in said ring member being constructed to communicate with said admission ports for the forward and rear ends of the cylinder in alternation 75 when said valve ring member is at the opposite limits of its movement.

In testimony that I claim the foregoing as my invention I affix my signature in the presence of two witnesses, this 5th day of December A. D. 1910.

REINHOLD A. NORLING.
